UNITED STATES PATENT OFFICE.

HERMAN ABRAMS, OF PHILADELPHIA, PENNSYLVANIA, ASSIGNOR TO CRESCENT
BRASS MFG. CO., OF READING, PENNSYLVANIA, A CORPORATION OF PENNSYLVANIA.

DESIGN FOR A WALL-BRACKET LIGHTING FIXTURE.

Application filed December 29, 1927. Serial No. 24,689. Term of patent 7 years.

To all whom it may concern:

Be it known that I, HERMAN ABRAMS, a citizen of the United States, residing at Philadelphia, in the county of Philadelphia and State of Pennsylvania, have invented a new, original, and ornamental Design for a Wall-Bracket Lighting Fixture, of which the following is a specification, reference being had to the accompanying drawing, forming part hereof, in which—

Fig. 1 is a top plan view; and
Fig. 2 is a front elevation showing my new design.

I claim:

The ornamental design for a wall bracket lighting fixture, as shown.

HERMAN ABRAMS.
